UNITED STATES PATENT OFFICE.

GUSTAV A. BARTH, OF ST. LOUIS, MISSOURI, ASSIGNOR TO PIERRE CHOU-TEAU, OF SAME PLACE.

DIRECT-ACTING ENGINE.

SPECIFICATION forming part of Letters Patent No. 397,959, dated February 19, 1889.

Original application filed August 20, 1888, Serial No. 283,220. Divided and this application filed November 27, 1888. Serial No. 291,950. (No model.)

To all whom it may concern:

Be it known that I, GUSTAV A. BARTH, a citizen of the United States, residing at the city of St. Louis, State of Missouri, have invented certain new and useful Improvements in Direct-Acting Steam or Pneumatic Engines, of which the following is a full, clear, and exact description.

My invention relates to improvements in direct-acting steam or pneumatic engines wherein the piston is reciprocated in the cylinder by the action of its valve without the intervention of valve-operating mechanism, and has for its object to vary the stroke of the piston while handling the machine when used for calking, riveting, mining, and other purposes.

The subject-matter of the present application is a division of application for United States Letters Patent filed by me in the United States Patent Office August 20, 1888, Serial No. 283,220. It comprises a cylinder bored out concentrically to two different diameters for different portions of its length and a piston working therein, a tubular piston-rod provided with inlet and discharge passages, a distribution-valve adapted to reciprocate within said piston-rod, a rod attached to the tubular piston-rod and extending through a cylindrical tube or casing projecting from and closing the inner end of the cylinder, a stock or holder secured to the outer end of the extension piston-rod and carrying a chisel or other appliance, and a supplemental arrangement of ports or passages controlled by a specially-devised valve for varying the stroke of the piston when starting from the inner end of the cylinder, the whole being mounted on wheels for facilitating the transport and application of the machine.

On the accompanying drawings, Figure 1 represents a central longitudinal section, broken away, of my improved direct-acting engine adapted for use as a chipping device in mining operations, the piston being shown at the outer termination of its stroke; Fig. 2, the continuation of Fig. 1, broken away; Fig. 3, a similar view taken diagonally to that in Fig. 1, the piston being shown part way along

the cylinder toward the outer end of its stroke; Figs. 4, 5, 6, 7, 8, and 9, transverse sections on lines 1 1, 2 2, 3 3, 4 4, 5 5, and 6 6, respectively, taken through the ports and valve shown at the lower part of Fig. 3; and Fig. 10, a detached view of the valve as seen with relation to the ports from beneath or at right angles to its position in Fig. 3.

Like letters of reference denote like parts in all the figures.

a represents the cylinder, which is bored out concentrically to two different diameters, extending in opposite directions from a plane at or near the middle of its length, and corresponding, respectively, with the diameters of its piston *b* and of a tubular piston-rod, *c*, which is formed in one piece with or secured to the piston *b*. The piston *b* and tubular piston-rod *c* are bored out centrally to provide a cylindrical chamber or cavity, *d*, which extends from its open end, where it is flush with the outer side of the piston *b*, to a suitable depth within the tubular piston-rod *c*, the inner end of which is extended by means of a rod, *c'*, passing through the inner end of the cylinder *a* and through a cylindrical tube or casing, *a'*, which projects therefrom, and closes the inner end of the cylinder *a* and forms a guide for the extension piston-rod *c'*.

To the end of the extension piston-rod *c'*, external to the outer end of the casing *a'*, is fixed a stock or holder, *h*, for receiving and holding the chipping-tool *i*, or other appliance, as the case may be.

In the outer open end of the cylindrical chamber or cavity *d* in the piston *b* and rod *c* is fitted and fixed a cylindrical flanged tube or sleeve, *j*, which is flush at its outer end with the outer side of the piston *b* and extends a certain distance within the chamber *d*.

Into the inner end portion of the tube or sleeve *j* projects the outer diametrically-reduced end portion of a cylindrical distribution-valve, *k*, which to the extent of that portion of its length beyond the shoulder of its reduced end is fitted to and capable of reciprocating within the chamber *d*, and is formed with a longitudinal central supply-passage, *l*, extending from its outer open end, inclosed

by the tube or sleeve *j*, to a suitable distance therefrom, one or more inlet-passages, *m*, being formed near the inner closed end of the supply-passage *l* through the wall of the distribution-valve *k*, and communicating with an annular space, *m'*, formed by a circumferential recess in the interior surface of the chamber *d*, in conjunction with the circumferential surface of the distribution-valve *k*.

10 *n*² are inlet-passages leading to the chamber *d* through the wall of the latter from the outside of the tubular piston-rod *c*.

15 *o* is an inlet-passage extending from the outside of the tubular piston-rod *c* beyond the inlet-passages *n*² through the wall of the tubular piston-rod *c* and through the inner end of the chamber *d*, with which it communicates behind the distribution-valve *k*, and *p* is an outlet-passage extending from the side of the 20 chamber *d*, at a suitable distance from the inner end of the latter, through the tubular piston-rod *c* to the outside of the latter toward its inner end.

25 *q* are exhaust-passages extending from the interior of tube or sleeve *j*, through the wall of and surrounding the latter, and thence longitudinally through the inner portion of the piston *b*, as indicated by dotted lines in Figs. 1 and 2, and tubular piston-rod *c* to a circumferential recess, *q'*, formed on the outside of the rod *c* toward its inner end beyond the outlet-passage *p*, by which arrangement the inner end of the tubular piston-rod *c* is closed for the purpose of cushioning the piston *b* and 30 rod *c* at the termination of their inner stroke.

35 *q*² is an exhaust-passage opening from the small portion of the cylinder *a* into the external atmosphere.

40 Steam or other motive fluid is admitted to the engine through the inlet-passage *r*, which opens into the cylinder *a* at the inner end of its larger portion, and is provided at its mouth with a suitable valve (not shown) for controlling the pressure.

45 In operation, the parts being in the position seen in Fig. 1, the operator locates the machine by means of its handle *s* and wheels *t* into the desired position for the work, and admits steam or other motive fluid through 50 the inlet-passage *r* into the cylinder *a* on the inner side of the piston *b*, as indicated by the arrows, where, circulating around the tubular piston-rod *c*, it passes through the inlet-passages *n*, annular space *m'*, and inlet-passages 55 *m* into the central supply-passage, *l*, of the distribution-valve *k*, and through the tube or sleeve *j* to the outer side of the piston *b*, which, with the tubular piston-rod *c*, is thereby forced toward the inner closed end of the cylinder *a*, 60 and, carrying with them the extension piston-rod *c'* and stock or holder *h*, causes the chipping-chisel *i* to strike upon the material to be dislodged. Meanwhile the outlet-passage *p* on reaching the exhaust-passage *q*² through 65 the wall of the small portion of the cylinder *a*, and the inlet-passages *n*, *n*², and *o* entering the same part of the cylinder *a*, and being

thereby closed to the ingress of steam, the steam which was behind and held the distribution-valve *k* in its outward position is exhausted through the passages *p* and *q*² and allows the distribution-valve *k* to be forced toward the inner end of its chamber *d*, so as to close the inlet-passages *n*, *n*², and thereby prevent the subsequent entrance of live steam 75 to the central supply-passage, *l*. As the distribution-valve *k* is approaching the end of its travel, it closes the mouth of the outlet-passage *p*, so that the steam then occupying the space between the distribution-valve *k* 80 and the inner end of the chamber *d* and that contained in the inlet-passage *o*, not being able to escape is compressed and acts as a cushion to the distribution-valve *k* in terminating its stroke. Simultaneously, by the inward movement of the distribution-valve *k*, 85 its outer reduced end uncovers the exhaust-passages *q*, through which and through the circumferential recess *q'* around the inner end portion of the tubular piston-rod *c* the 90 steam from the outer side of the piston *b* is exhausted through the passage *q*² into the atmosphere, and the steam contained in the cylinder *a* on the inner side of the piston *b* presses upon the annular surface of the latter, and thereby forces the piston *b*, with the tubular piston-rod *c*, toward the outer end of the cylinder *a*, or so as to withdraw the chisel *i* from the material until the inlet-passage *o* passes just beyond the outer end of the small 95 portion of the cylinder *a* into the larger portion of the latter, when the steam from the space on the inner side of the piston *b* enters the passage *o* and forces the distribution-valve *k* outward to its original position, or with the 100 shoulder of its reduced end bearing against the inner end of the tube or sleeve *j*, thereby again opening communication between the inlet-passages *n*, *m'*, *m* for admitting the steam to the outer side of the piston *b* and to the 105 passage *n*² for supporting the distribution-valve *k* in the outward position while the piston *b* is performing its return-stroke.

The above description applies to the normal operation of the machine, with the piston 115 and its appendages making a full stroke in the cylinder; but in practice it is found desirable to shorten the stroke of the piston for producing short and rapid blows of the chisel against the material to be dislodged. To this end there are formed through the wall of the cylinder *a* at the lowest or other convenient part of its small portion between the inner end of the larger portion and the main exhaust-passage *q*² (see Fig. 3) supplemental 120 ports or passages 1, 2, 3, 4, 5, (more or less,) which are in line, at suitable distances apart, with the inlet-passage *o* to the chamber *d*, containing the distribution-valve *k*, and with a passage, *b'*, which is formed through the wall 125 of the cylinder *a* at the inner end of its larger portion. The ports or passages 1, 2, 3, 4, 5, and *b'* open from the cylinder *a* into a cylindrical chamber, *z*, which is formed longitudi- 130

nally in the wall of the cylinder *a* and closed at both ends. Within the chamber *z* is fitted a cylindrical valve, *y*, to which is attached an operating-spindle, *w'*, extending to the outer end of the machine and provided thereat with a suitable handle, *u'*. The wall of the valve *y* is cut away in a series of successive notches or spaces equal in number to the ports 1, 2, 3, 4, and 5, and corresponding in length, respectively, with the arithmetical progressive additions of their diameters—that is to say, the circumferential length of the first notch around the valve *y* will be that due to the diameter and necessary cover of port 1, the second notch that due to port 1 plus port 2, the third notch to port 1 plus 2 plus 3, and so on throughout the entire series, the fifth notch being prolonged longitudinally with the valve *y* to beyond the passage *b'* for allowing the latter to normally remain open to the chamber *z*, except when closed simultaneously with the ports 1 2 3 4 5.

The position of the valve *y*, as seen in Figs. 3 and 10, is so that its first notch or space is opposite to port 1 and its other spaces in the various relative positions to the ports 2, 3, 4, 5, and *b'*, as seen respectively in Figs. 4, 5, 6, 7, 8, and 9—that is to say, the entire series of ports 1, 2, 3, 4, 5, and *b'* are open to the chamber *z*. As soon, therefore, as the mouth of the inlet-passage *o* during the outer stroke of the piston *b* arrives opposite to port 1 the steam, coming from the larger portion of the cylinder *a* through the passage *b'* and chamber *z*, passes through port 1 and passage *o*, and forcing the distribution-valve *k* outward reverses the movement of the piston *b* in the same manner as if the passage *o* has traveled to its full

extent to the inner end of the larger portion of the cylinder *a* for receiving the pressure 40 in making a full stroke; or, in other words, the stroke of the piston *b* is thereby shortened to the extent of the distance between port 1 and the commencement or inner end of the larger portion of the cylinder *a*. By successive partial rotations of the valve *y*, as indicated by the arrows, the ports 1, 2, 3, 4, and 5 may be successively closed for varying the stroke of the piston *b* according to their respective distances from the larger portion of the cylinder 50 *a*; or all the ports 1, 2, 3, 4, 5, and *b'* may be closed simultaneously when desired to make the full stroke of the piston *b*.

I claim—

1. In a direct-acting steam or pneumatic 55 engine, the combination of the cylinder having inlet ports or passages and an outlet port or passage, said passages opening into a chamber closed at both ends and containing a valve, with the inlet-passage in piston-rod to the 60 chamber containing the distribution-valve, substantially as shown, and for the purpose described.

2. The combination of inlet ports or passages and valve *y* in closed chamber *z*, with 65 outlet-passage *b'* from cylinder *a* and inlet-passage *o* in piston-rod *c*, substantially as shown, and for the purpose described.

In testimony whereof I affix my signature, in presence of two witnesses, this 24th day of 70 November, 1888.

GUSTAV A. BARTH.
